CIRCUIT BREAKER

Willis Bevan Whitney, Edmund Basil Wedmore, and Alexander Morris Cassie, London, England, assignors to The British Electrical and Allied Industries Research Association, London, England, a British company

Application April 25, 1932, Serial No. 607,470
In Great Britain May 9, 1931

38 Claims. (Cl. 200—150)

This invention relates to electrical switches or circuit breakers wherein a supply of fluid such as a liquid or gas, or a mixture of both is provided for extinguishing the arc set up on interruption of the circuit. The invention has application to other circuit interrupters such as lightning arresters and fusible cut-outs, in which an arc may be set up at the moment of discharge or at the moment of the fuse interrupting the 10 circuit.

It has already been proposed to provide a high tension switch having a closed casing containing an insulating liquid such as oil with a piston which is moved upon opening of the switch so as to generate pressure which is employed upon separation of the switch contacts to cause oil to flow under pressure between the arcing contacts. The present invention is more particularly concerned with switches in which the blast of 20 fluid is driven across one electrode in this way by means of the movement of a piston.

According to the present invention, an electrical circuit breaker, switch or other circuit interrupting device has the electrodes arranged so that the arc between them is struck in a confined or substantially closed arcing space and a piston or equivalent pumping device is provided in such a way that the pressure set up by the products of the arc acts on both of its faces so as to cause the piston to move during arcing between the electrodes in order to squeeze the extinguishing fluid in that arcing space and to force it into contact with at least one of the arcing electrodes before escaping to the other side of the 35 piston.

Constructions of circuit breakers are already known, in which the arc products have been squeezed out of the arc gap by pressure set up independently of the arc itself. The present invention employs the energy of the arc drawn between a pair of electrodes to squeeze the arc products from the arc gap between the electrodes by utilizing the principle of the hydraulic press so that the gases after they have been squeezed 40 from the arc, exert pressure upon a surface of a movable member of relatively larger area than that of the surface acted upon to oppose the movement of that member. The moving member compresses or drives fluid into the arc gap and thus may be arranged in such a manner that the part of the arc subjected to the blast in the arc gap cannot escape from the region subject to the high intensity of pressure.

A unit of a circuit breaker in accordance with 55 the invention may be arranged for mounting on

the leading-in insulators of many existing circuit breakers with little or no alteration to the existing parts. The circuit breaker may be arranged to set up two or more breaks in series, and a series of baffle plates forming shallow 60 chambers between them in accordance with our United States patent application Serial No. 563,390 dated 17th September, 1931 may be employed so that the moving switch contact moves through apertures in the baffle plates or moves past the 65 edges of the baffle plates. The invention is not, of course, limited to switches or circuit breakers in which the electrodes are positively separated, but it may be applied to other circuit interrupters, such as fusible cut-outs, lightning or surge 70 arresters and so forth.

In order that the invention may be clearly understood and readily carried into effect, a number of forms of construction of circuit interrupters in accordance therewith will now be described 75 with reference to the accompanying drawings, wherein:—

Figure 1 is a sectional elevation taken through a diametrical plane to the left of the centre line and with the outer casing in section to the right 80 of the centre line showing one form of construction of circuit breaker in accordance with the invention;

Figure 2 is a sectional elevation of a detail 85 showing a constructional variation of Figure 1;

Figures 28 and 29 are two elevations at right angles showing a method of disposing the units of a three-phase circuit breaker with a double break in each phase according to the present invention; and

Figure 30 is a sectional plan on the line XXX—XXX in Figure 28.

In the form of construction illustrated in Figure 1, the lead-in insulator 1 which may be suspended from the lid of an enclosing vessel or oil tank is fixed at the bottom to an enclosure 2 generally of cylindrical form. The cylindrical wall of 2 is generally of metal, but is encased in an outer covering 3 of insulating material, while any screw-heads are covered with insulating compound as shown at 3a. The metal wall 2 is turned in at the bottom at 4 to receive a base 5 of insulating material which is recessed centrally at the top to receive a gland 6 also of insulating material. This is free to move slightly radially and axially with respect to the moving switch contact 7, but is retained in its recess by a cover plate 8 held in position by screws. The base 5 and the associated parts are held in position by a tubular member 9 screwed into the inner wall 2 of the container. The inner cylindrical wall 40 of the member 9 forms a cylinder of reduced diameter to receive the lower disc 10 of a trunk piston 11. The upper disc 12 of the piston 11 slides directly within the inner surface of the wall 2. The piston 11 is normally held up in the position shown in the drawings by a rather light spring 13 which, in the position shown, is extended to its limit. The piston 11 also has a number of circumferentially spaced castellations 14 for the purpose of increasing the guiding area of the upper part of the piston and yet of allowing of access from the central space above the piston to the cylinder wall 2 for the purpose which will appear below. Of course, the castellations 14 might be used as stops for the piston stroke if they were arranged to come into contact with the metal top plate 15 of the container, but as illustrated this is not the case as the spring 13 is fully extended before that state of affairs is reached.

After the base parts, the spring 13 and piston 11, are placed in position, the cover or top plate 15 carrying the fixed contacts 16 may be screwed in. The contacts 16 are screwed into a depending sleeve 17 formed in two parts, the lower part 17a of which fits a bore of the piston 11 and the upper part 17b of which is screwed into a recessed plate 18 fixed by screws 19 to the top plate 15. The upper part 17b of the sleeve 17 is provided with windows 20 through which pressure at the centre has access to the upper disc 12 of the piston 11. The lead-in conductor 21 is brought through the insulator 1 and screwed into the metal top plate 15 and therefore is directly electrically connected with the fixed contacts 16. One or two seep holes 22 are provided through the

contacts 16 to prevent the accumulation of a pocket of gas outside these contacts. Seep holes may also be provided in the top plate 15 at 23 and in the recessed part of the plate 18 if it is desired to prevent the trapping of a cushion or pocket of permanent gas, and the seep holes 23 may be extended, for example, by tubes such as shown in dotted lines at 24 to imprison gas or vapour in the upper part of the contact when it is desired to produce a cushioning effect. Again, the seep holes may be drilled through the sides of the casing 2 and 3 at the required height for the same purpose. The container 2 is provided with an exhaust port at 25. The moving contact 7 is shown in full lines in its uppermost position corresponding to the closed position of the switch and is shown in dotted lines at 7a in the fully retracted position which it may take up when the switch is opened. Of course, a wider gap between the bottom of the container 2 and the top of the moving contact 7a can be obtained when a longer stroke is available.

In operation, the moving contact 7 is drawn down for example by the usual cross bar; the contacts 16 being fixed to the cover plate do not follow it, but as soon as contact is broken an arc is set up between the contacts 7 and 16 and the pressure from the products of arcing acts on the lower surface of the piston 11 within the tubular member 9 and is also transmitted through the central passageway within the contact 16 through the windows 20 on to the top of the piston 11 within the cylindrical wall 2. As this upper surface is of greater area than the lower exposed surface there will be a downward unbalanced pressure on the piston 11 so that this will commence to move downwards, compressing the spring 13 and forcing oil from below the piston through the central passageway in the fixed contacts 16 so that the oil will be forced across and along the surfaces at which the arc is formed. This action continues until the upper disc 12 of the piston uncovers the exhaust port 25; then any excess pressure is released and the spring 13 is enabled to raise the piston 11 again into the normal position shown in the drawings.

There are thus spaces within the switch container 2 on opposite sides of the piston 11 which may be referred to as the primary and secondary pressure-retaining chambers, each of which may, however, consist of more than one space in communication. In Figure 1, the space within the tubular member 9 below the piston 11 forms the primary pressure-retaining chamber, while the secondary pressure-retaining chamber consists of the whole of the space above the moving contact 7 within the fixed contact 16 and sleeve 17 and also that above the top of the piston disc 12. The primary and secondary chambers thus communicate with each other through one or more comparatively constricted apertures which in Figure 1 are constituted by the passageway through the fixed contact 16. Moreover, as the switch contact 7 is situated in the primary chamber which contains extinguishing fluid, when the piston movement starts, the total space enclosed within the walls of the primary chamber is decreased by an amount smaller than the increase in space in the secondary chamber and this results in squeezing the extinguishing fluid so that it washes over a surface of the switch contact 7 before it escapes through the passageway in the fixed contact 16 into the secondary chamber. The electrodes are thus preferably so formed that one of them provides, at least in part, a passage

- through which the extinguishing fluid flows and the flow of this fluid is assisted by the pressure of the hot products from the arc acting upon the upper face of the piston 11 to which they have 5 access after they pass through the passageway in the fixed contact 16 and this pressure acting upon the upper face of the piston 11 acts against the retarding effect on the lower face of the piston of the pressure due to the hot products from 10 the arc. When as in Figure 1, the area of the upper face of the piston is sufficiently greater than the area of the lower face, the unbalanced force exerted by the arcing products alone causes motion of the piston as described above and as a 15 result, the oil or other extinguishing fluid is forced by the piston through the central aperture in the contact 16 and is thus forced across at least one electrode of the switch in order to extinguish the arc.
- 20 In actual practice a circuit breaker unit as shown in Figure 1 may have the following overall dimensions, viz., a height of 8 inches and diameter of 6 inches with the moving contact 7 having a diameter of $\frac{1}{8}$ of an inch. It was found 25 that with such a construction, a series of seven repetition tests resulted each time in the successful interruption of a highly inductive circuit carrying an alternating current of 500 R. M. S. amperes at a frequency of 50 cycles per second 30 derived from a power transformer stepping up from 6600 volts to 22,000 volts and giving a recovery voltage of 21,000 volts across the single gap employed. The gap between the contacts 7 and 16 was limited to 0.8 inches and the largest arc 35 gap at arc extinction was 0.34 inches. All tests were cleared in less than one cycle of arcing. In some cases the arc was extinguished before the separating contacts 7 and 18 had formed a gap of 0.2 inches corresponding to a dielectric 40 strength of over 100,000 volts per inch. As an indication of the improvement attained by this method of arc rupture as compared with a plain break in oil, it may be mentioned that in the latter case, arcs of upwards of 10 inches in length 45 would be drawn with the same applied voltage and current per break, giving an arc energy output many times greater than that liberated in the above seven tests with a current breaker in accordance with the present invention. In these 50 tests, the unit was completely filled with oil except for a small cushion of approximately 7 c. c. trapped in the top contact holder 17b and the head of oil in the outer tank, surrounding the arcing container 2, measured upwards from the 55 top of the exhaust port 25 was 5 inches in the first five tests and 9 inches in the last two. The average piston travel during the first 1/50th second after commencement of arcing was $\frac{1}{3}$ of an inch.
- 60 The limitation of the gap between the electrodes was obtained by stopping the movement of the moving electrode 7 while allowing it to remain in electrical contact with the moving cross bar by way of an extensible connection. A 65 somewhat similar method of obtaining a limited gap without interference with the straight-through movement of the cross bar of a circuit breaker will be described below in connection with Figure 17. As pointed out in the specifications 70 of our United States patent applications Serial No. 180,204 filed 1st April, 1927, and Serial No. 411,307 filed December 3, 1929, the use of a short gap is advantageous as it reduces the length and energy of the arc within the gap to a minimum 75 so that the arcing surfaces of the counter

contacts can be kept in a region where the fluid blast flows into the gap at high velocity and thus efficiently scours away the hot products of the minimized arc energy and cools the arcing surface. Thus, when the current, in its alternation, reaches zero, conditions of temperature and fluid density are set up which prevent the applied voltage from restriking across the gap subsequently thus extinguishing the arc.

80 In order to prevent knock at the end of the stroke and to ensure that the stroke of the piston lasts for two cycles or more in order to secure a sufficient duration of blast for the extinction of the arc within a cycle and to provide an adequate factor of safety, it is desirable in some cases to introduce a dash-pot effect.

85 One method of doing this is illustrated in Figure 2, which illustrates a modified construction of the circuit breaker shown in Figure 1 and only includes the portion round about the exhaust outlet 25. The upper part 12 of the piston 11 in this case has a depending edge portion 12a which during the first part of the downward stroke gradually closes the main exhaust outlet 25 so that the oil between the outer cylinder 2 and the wall of the piston 11 has from that instant to escape through an auxiliary outlet or outlets 25a in the wall 2 of the container so as to produce a dash-pot effect. Towards the end of the stroke and before the lowermost outlet 25a is covered, the top of the piston 11 uncovers the outlet 25 allowing of exhausting of the products above the piston 11. A small hole or passage 9a is also provided in the tubular member to allow a rapid start off of the piston 11. 90 The remaining reference numerals are as in Figure 1 so that the construction can be clearly appreciated.

95 In Figure 3, the construction is shown slightly modified in the upper part, but the same in the lower part as in Figure 1. In this case, the piston 11 itself carries the relatively fixed contacts 16 and consequently provision has to be made to carry the current to these contacts. This is effected by means of a series of flexible leads 26 100 serving as pigtails and clamped by screws at the upper end to the plates 18 fixed to the top metal plates 15.

105 The action in this case is similar to that in Figure 1, except that when the piston 11 moves downwardly, the contacts 16 move with it, but, as explained below, not as rapidly as the moving switch contact 7. Thus, when the arc products pass out from the exhaust port 25 and the piston 11 rises again, it carries up with it the contacts 16 thereby 110 increasing the separation between them and the moving contact 7.

115 The form of construction described will tend automatically to keep the gap short because if the lower contact moves down much quicker than the nozzle contact carried by the piston the increased length of arc will lead to the generation of increased pressure and hence to a greater difference of force on the two sides of the piston so that the latter will be accelerated downwards.

120 If, however, owing to excessive length and arc energy of the arc, the moving piston 11 with its contact 16 begins to overtake the moving contact 7, the length of the arc and hence its energy, is decreased so that the downward force on the outer 125 piston is decreased and it tends to lag behind again. If, alternatively the reduction in length is so fast that there is not time for the reduction in arc energy to affect the piston, the nearer approach of the opening in the contact 16 to the end 130

135

140

145

150

of the electrode 7 will produce a throttling effect on the escaping oil which will become more and more powerful as the two electrodes approach one another and, since the only means for escape of the oil or other fluid from the arcing chamber is through the contact 16, this throttling action will itself slow down the rate of movement of the piston 11 and allow the moving contact 7 to draw away from it again. The arrangement thus constitutes an example of a self-adjusting arc gap. The adjustment may be further modified by the relative shaping of the counter electrode surfaces so as to produce either a rapid or slow throttling for given rate of linear approach.

It is, of course, important for the downward movement of the piston and consequently the forcing of oil through the passageway in the contacts 16 not to be delayed due to unnecessarily high inertia of the moving parts or other cause.

A form of construction is shown in Figures 4 and 5 which is designed to reduce the time taken in the pistons starting. In this construction the container 2, connected to the lead-in insulator 1 and lead 21 and having a covering 3, is of much the same form as before, being flanged at the bottom at 4 and receiving the base members 5, 6 and 8. In this case, however, instead of the tubular extension 9 a clamping ring 27 is screwed into the container to hold the base components in position. Furthermore, the container 2 is internally shouldered at 2a and a cage 28 is inserted from the top to rest on the shoulder 2a. This cage may be a casting bored to receive a number of pistons 11; for lightness these pistons are hollow and may be closed at the bottom by plugs 11a which also act as stops for the pistons at the upper end of their strokes. The whole cage is held in position by a screwed-in ring 29. In this case, the fixed contacts 16 are screwed into the inner bore of the cage 28. The pistons are shouldered, the external cross-sectional areas of their stems presenting the end surfaces exposed to pressure below the contacts 16 and upper disc 12 of greater area being exposed to the pressure above the contacts 16. Seep holes are provided at 22 and 23 as is Figure 1. Each piston 11 has its own independent spring 13. In this case, when the moving contact 7 is moved downwardly and an arc is struck between it and the fixed contacts 16, the pressure acting on the greater area at the top of each piston 11 causes it to move down quickly against the springs 13 as the pistons are made very light and thus oil is forced rapidly into and through the passageway in the contacts 16, and this goes on until the disc 12 uncovers the exhaust ports 25. These ports all open into an annular manifold 30 which itself opens at one part of the circumference by way of a port 31 through the container wall 2 and insulating cover 3 into the outer oil tank. In Figure 4, also, the contact 16 is shown with a diverging exhaust funnel so as to assist the rapid escape of the hot gases from the arc gap.

In the form of construction illustrated in Figure 6, the piston 11 has its upper part 12 sliding in a cylinder formed by a downward extension 34 from the cover 15 of the container 2, while the lower part 10 of the piston 11 slides in the lower part of the container 2. The moving contact 7 has its upper part hollow and in communication with the space below the piston 11 through lateral ports 35. The fixed contact 16 is supported in a central insulating disc 36 screwed into the cover 15 and is connected to the lead-in conductor passing through the insulator 1. In this case,

when the arc is struck between the contacts 7 and 16, the pressure set up acts directly on the top of the piston 11 and is transmitted through the hollow bore of the upper part of the contact 7 to the space below the piston where it acts on a larger effective area. The piston is therefore, forced upwards telescoping into the cylindrical extension 34. Owing to its shape it sweeps all the oil and products of arcing completely out from the inside of the cylinder 34, the products passing through the contact 7 to the space below the piston and ultimately through the exhaust port 25, when the piston 11 has risen far enough to uncover that port. When the pressure below the piston is exhausted, the circuit interrupted and the arc extinguished, the piston 10 is reset due to its own weight. This resetting by gravity has an advantage, in cases in which it is desirable that there shall not be an increasing retardation of the piston as it travels forward as would be the case if the piston moves against the action of a spring.

Figure 7 illustrates another telescoping arrangement providing rigid walls for the arc chamber and a rigid outer container. In this form of construction, the whole unit is extremely compact and increases its length downwardly during the arcing process and subsequently is shortened again. As before, the container 2 is shown with the insulator 1 with the lead-in conductor mounted on the cover 15. The piston 11 has a tubular extension 36 which slides downwards with the lower plate 37 of insulating material, through which the movable contact 7 can slide. The products of arcing act on the whole of the upper face of the piston 11, but only on the central part of the lower face. The upper contacts 16 are carried by the piston and are connected to the lead-in by pigtails 26 as in Figure 3 so that the method of operation is very similar to that of the form of construction shown in Figure 3.

It will be seen that in the type of construction illustrated in Figure 7, the overall height of the container 2 for given length of the piston stroke is much less than in the constructions already described. The downward extension in length during arcing can take place quite conveniently in this construction, even in the usual case in which the moving electrode 7 is carried on a cross-bar, since the cross-bar movement will be in the same downward direction. After the arc has been extinguished, the extended wall 36 is retracted back into the relatively short cylindrical container 2, as mentioned above. Thus, for a given stroke of cross-bar and piston and for a given distance between the insulator 1 and the cross-bar in the full open position of the switch, this construction allows a larger clearance between the cross-bar and the bottom of the container 2 than do the constructions already described. Longer clearances of this kind are advantageous as they make it easier at given voltages to prevent or minimize corona discharge which might otherwise take place where the overall clearances within which the container has to be fitted are small.

This form of construction also illustrates a method of combining certain of the advantages of the downwardly extendable construction with a self-adjusting arc gap as illustrated in Figure 3 and with the further useful feature that the external sliding surface of the cylinder 11 is open to inspection and cleaning without opening up the container 2.

In Figure 8 a construction is shown which in general is similar to Figure 7. This construction,

however, has certain advantages in that it allows of inspection of two sliding surfaces and of the spring 13 without opening the container 2; also, it may be fitted with an auxiliary contact 49a 5 suited to provide a self-adjusting arc gap independently of the movement of the contact 7. The auxiliary contact 49a is shown mounted on a sliding member 49 within the tubular downward extension 71. It is pressed down by a light spring 50. If now the moving contact 7 descends 10 too quickly and there is excessive differential pressure generated, the oil forced up by the piston 11 below the member 49 will lift the latter and the arc will pass from the fixed contact 16 to the upper tip of the member 49 and then 15 across the very small gap to the moving contact 7. The member 49 has deep holes 51 and inclined ports 52 so that the oil forced up can pass through the ports 52 and through the space between the contacts 7 and the member 49. 20

In Figure 9, a construction is shown in which the whole of the container 2 moves relatively to the fixed insulator 1 and the piston 11, which has attached to its lower surface a metal bellows or 25 springy tube 39 and this figure illustrates a type of construction particularly suited for the separation and complete ejection of the dirty used oil from the container 2 and from the outer switch tank in which the container may be immersed. 30 The bellows 39 may conveniently be made of thin metal such as rustless steel or tombac. As a matter of fact, in Figure 9, arrangements are shown for ejecting the used oil through the centre of the insulator 1. When the arc is struck between the contacts 7 and 16, the pressure within the bellows 39 acts on the central part of the underneath face of the piston 11 and the pressure also acts on the top of the piston 11, which, as already mentioned, is in this case, fixed to the lower part of the insulator 1 and cannot move. 35 A thimble-shaped valve 40 is lifted by the pressure against a light spring 41 and it enters the lower part of the tubular member 95 with the result that its ports 42 are cut off. The differential pressure, therefore, is able to lift the whole container 2 against the return spring 13 so that the 40 space above the piston 11 increases in volume and that within the bellows 39 decreases squeezing the oil out through the upper contacts 16. As soon as the top of the casing 2 rises above the exhaust port 13, the pressure above the piston 11 is 45 exhausted between the inner and outer tubes 97 and 98 and thence for example, through a non-return valve or swan-neck, not shown, to a drain, and the spring 13 is able to push down the container 2 again. During this time, the volume 50 within the bellows 39 increases so that the bellows expand and the valve 40 is drawn down. At the same time, the space above the piston 11 is decreasing so that any remaining used oil is forced out through the ports 42 and through the tube 97 to the drain already mentioned.

In a further form of construction illustrated in Figure 10, the general arrangement is very similar to that of Figure 3, except that the upper contact 16 is not hollow and the piston 11 carries a series of baffle plates 44 which are somewhat similar to those set forth in our United States patent application Serial No. 563,390, filed 17 September, 1931. The remainder of the construction is somewhat similar to that shown in Figure 3 and the same reference numerals have been employed. When the switch is opened and the contact 7 descends, an arc is struck between it and the upper contact 16. The arc products

move in one general direction through the chambers between the baffle plates 44 into an axial passage 45 and the pressure is thus communicated to the whole upper surface of the piston 11. The pressure acts on a smaller area below the piston so that the latter is forced downwards against the spring 13, but the moving contact 7 moves more quickly, drawing the arc past the openings between successive baffle plates. In this case, as in all the cases in which the upper contact 16 is carried on the piston, there is an effect of a self-adjusting arc gap because if the piston moves down too quickly following the contact 7, the pressure is automatically reduced tending to make the piston move more slowly.

Figure 11 shows a further modification arranged to break up the arc into a number of arcs in series. The container 2 and the piston 11 with its spring 13 are arranged much as in Figure 10, except that the cylinder 17 is extended downwards and the upper contact 16, in this case, is fixed and is carried from the top cover 15. A series of baffle plates 44 is employed which are somewhat similar to those set forth in our said United States application Serial No. 563,390. In this case, however, they are inclined instead of being horizontal to provide easy flow of the fluid and are stationary, being mounted on the tubular extension 17 from the cover 15 instead of being mounted on the piston 11 as in Figure 10. The baffle plates 44 are provided with conducting tips 46. The action therefore as the contact 7 moves down is as follows:—An arc is first struck between the contacts 7 and 16; after the tip of the contact 7 has passed the uppermost conducting tip 46, the 100 arcing is transferred to that tip due to the action of the fluid blast acting through the passageway 48 so that then there are two arcs in series one between the contact 16 and the tip 46 and the second between the latter and the contact 7. An 105 additional series arc is formed in a similar way as the contact 7 passes each of the conductive tips 46 and the arcs which are anchored to the conducting tips 46 and cannot escape through the outlet passages are subjected to a scouring 110 and squeezing action due to the movement of oil under pressure between the baffle plates 44. The outer ends of the passages between the baffle plates 44 are controlled by the piston 11 so that the outlet is varied and increases as the piston 11 descends under the action of the resultant differential pressure upon it. There is, therefore, a tendency for the outlet to open more quickly for heavy currents than for small currents. The oil below the piston 11 is thus forced through ports 47 115 to the inside of the sleeve 17, through ports in the insulating plate 48, across the arcing surface of the electrode 7 and through the baffle chambers to the top of the piston 11, being ultimately exhausted through the exhaust port 25.

Figure 12 shows another construction in which the movable electrode 7 moves through a series of baffle plates 44 similar to those shown in said United States application Serial No. 563,390. The pressure from the arc passing through the 120 baffle passages acts on the upper face of the piston 11 and the only back pressure is that acting on the lower edge of the piston. The piston, therefore, is forced down against the spring 13 and oil surrounding the contacts 7 and 16 is 125 squeezed out through the passages between the insulating baffle plates 44.

Figure 13 illustrates the invention in its application to a fusible cut-out. The device has a container 2 and an upper cover 15, as before, and

a differentially operating piston 11 which under the differential pressure set up on interruption of the circuit is forced down against a spring 13. The piston slides on the inside of an inner cylinder 53 and also on an inner insulating casing 54 which houses the fuse wire 55 extending between terminal blocks 56 and 57. The casing 54 has baffled windows 58 through which the pressure set up by the interruption of the circuit acts on the upper and lower faces of the piston 11. The movement of the piston forces oil through the lower window 58 into contact with the fuse wire at the point of rupture. The lower contact block 57 is engaged by spring fingers 59 electrically connected to the lead-in 60 and the whole is mounted on the insulator 1. In order to renew the fusible element 55, the inner casing 54 is unscrewed from a partition 61 to which the other lead 60a is attached and the complete central unit lifted out by the handle 62 carrying the top cover 15 with it.

In a similar way, Figure 14 illustrates the invention applied to a lightning arrester or surge interrupter. The high tension line is carried through an insulator 1 and the whole device is mounted in a container 2 which houses an inner cylinder 53 within which the differentially acting piston 11 slides. The electrodes 63 are shown as spherical electrodes but can obviously be of any type, for instance, plug and socket electrodes although in a surge or lightning arrester, they would not normally be in contact. The upper electrode is surrounded by a sleeve 64 preferably of insulating material. This sleeve 64 if connected by an extensible connection to the incoming lead 21, could be made in the form of a tubular contact, in which case the piston 11 or the cylinder 33 would be of insulating material.

In this case, the descent of the piston 11, in addition to forcing oil over the surfaces of the electrodes and out through the sleeve 64, causes an increased separation of the electrodes because the lower part of the piston 11 presses on a spider 65 which descends against the action of a spring 66 carrying with it the lower electrode 63. When the piston 11 uncovers the exhaust port 25, the pressure above the piston is relieved and the spring 66 is able to return the lower electrode 63 into the normal position, as shown. The insulator 1 passes through a protecting hood 67 and the lead-in conductor may be connected to the high tension line, if desired, through a limiting resistance, which, alternatively may be connected in series with the lead 68 and earth. The connection from the lower electrode 63 to earth 55 is shown at 68.

Figure 15 shows a construction of circuit breaker for providing two arcs in series, each of which is in connection with a vent passage leading to separate expansible vessels. The upper contact 16 is a hollow contact carried from a depending sleeve 17 and insulated from an intermediate contact 69 which is mounted on an open spider 70 and is pressed down by a light spring 71. When the circuit breaker is closed, the movable contact 7 presses up the contact 69 against the spring 71 into contact with the fixed contact 16. The piston 11 is a composite piston, the upper part 72 of which is insulated from the lower part as shown by a ring 73 of insulating material.

Upon opening circuit, the spring 71 first keeps the intermediate contact 69 down against the moving contact 7 so that an arc is first struck between the contacts 16 and 69. The pressure of the arc products is conveyed through ports 74 to the space below the upper lip of the piston 11

and through ports 75 to the internal upper surface of the piston 11 itself. The differential pressure causes the piston and its member 72 to rise against the action of the spring 13 thus forcing oil through the ports 75 over the arcing surfaces of the contacts 16 and 69. At this stage, the contact 79 meets its stops so that the continued movement of the movable contact 7 causes the latter to leave the contact 69 thus striking a lower arc.

A part of the oil now passes the spider 70 and under increased pressure passes through the hollow bore of the movable contact 7 and out through lateral ports to the space below the piston 11 thereby increasing the upward pressure on the latter. When the piston 11 rises above the exhaust port 25, the pressure below the piston is relieved. At the same time the roof portion of the piston member 72 has risen above the additional ports 25a and the arc products in the upper part are able to escape through the hollow upper portion of the depending sleeve 17 and out through outlets 25b in the top plate. The piston is afterwards reset by the spring 13 or by gravity.

In a modified form of the construction illustrated in Figure 15, the intermediate contact 69 with its spider 70 and light spring 71 may be omitted. In this case the moving contact 7 makes direct contact within the fixed electrode 16 and the passageway in contact 7 is extended downwards further than shown in Figure 15, and the outlets from the passageway are placed lower so as to allow venting to take place first below the insulating barrier 75a when the moving contact 7 is just leaving the contact 16.

The action upon separation of the electrodes 110 is then as described above, except that the arc products immediately escape towards either end of the enclosure through the passageways in the contacts 16 and 7 and oil or other extinguishing fluid is squeezed into the arc gap from all sides 115 by the action of the pressure upon the ends of the differential piston 11 and its upper member 72.

Figure 16 illustrates another form of construction but making use of a double bellows. This 120 construction employs a convenient method of venting clear of the guide surfaces which can be used in place of the ports 25 used in the solid type of constructions so far illustrated, and also employs means for minimizing the surface area 125 of the guiding surfaces, and the entire guiding surfaces are arranged so that they are not subjected to the action of the arc products and are open to inspection without opening the arcing chamber or upper container. In this case, metal 130 bellows are attached both to the upper and lower surfaces of the piston 11 to produce the differential areas on its opposite surfaces. This enables a containing vessel to be entirely dispensed with and the piston 11 is furnished with lugs 135 or ears 76 which are guided on outside guide rods 77. Springs 78 also encircle these guide rods 77 and press the piston 11 up into the position illustrated. The guide rods 77 are secured to the upper plate 79 and the lower plate 80 of the device, the whole device being carried from the lead-in insulator 1 to which the upper plate 79 is secured. In this case, the upper contact 16 is carried by the piston 11 and is a hollow contact as in many of the previous forms of construction 140 illustrated. It is connected to the leading-in conductors by pigtails 26 and between it and the pigtails, a number of metal plates or discs 81 are mounted. The purpose of these is to cool the products from the arc and condense any vapour 145 150

to prevent it being deposited on the inner walls of the upper bellows 82.

In operation, the movable contact 7 descends when the switch is opened; the pressure of the arc products acts directly on the lower surface of the piston 11 and passes through the upper contact 16 and between the discs 81 so as to act on the top surface of the piston. The piston consequently descends, extending the upper bellows 82 and compressing the lower bellows 83 and so squeezing the oil in the latter between the arcing surfaces of the contacts 7 and 16 into the space enclosed by the upper bellows 82. In this case, the piston cannot itself uncover exhaust ports, therefore, in order to exhaust the pressure from the upper space without providing ports in a guiding surface, small non-return valves 84 are provided normally spring-closed. At the lower end of the stroke, however, these valves about 20 against a corresponding number of studs 85 and the valves are thus opened, relieving the pressure in the upper bellows 82, whereupon the spring 78 is able to raise the piston again into the position shown in the drawings.

The form of construction shown in Figure 17 also employs bellows and this construction is particularly adapted for use when an extinguishing fluid such as hydrogen or helium is employed which it is desired to conserve. The circuit breaker in fact is completely sealed, the working spaces for the fluid being of annular shape and each lying between a pair of bellows. The stationary parts of the apparatus consist of the lead-in insulator 1 with its stem 1a and upper and lower plates 79 and 80 insulated from each other by the insulating cylinder 17. The rest of the apparatus rises against the action of the spring 13 upon interruption of the circuit. The upper bellows 82 and 82a enclose an annular space while the lower bellows 83 and 83a enclose an annular space of smaller cross-sectional area. When the circuit is opened, pressure from the arc between the contacts 16 and 7 passes through metal plates or discs 81, similar to and for the same purpose as those shown in Figure 16, into the annular space between the bellows 82 and 82a. The pressure is also transmitted through passages 86 in the plate 80 to the annular space between the lower bellows 83 and 83a so that the structure is raised against the spring 13 by the differential pressure acting on the plates 79a and 80a. The upper bellows 82 and 82a are thereby extended and the lower bellows 83 and 83a contracted so that fluid in the lower space is squeezed out and forced up between the arcing surfaces of the contacts into the space between the upper bellows 82 and 82a. When the arc is extinguished and the gas has cooled, the pressure subsides and the spring 13 presses down the whole structure into the position shown in Figure 17. It is clear that the movable contact 7 has to slide without allowing of any leakage from its arcing surface to the exterior. The contact 7 is therefore flanged at 7a and the flange is connected to the plate 80 by an internal bellows 87. This bellows expands when the contact 7 moves downwards without breaking the seal between the inside of the structure and the outside. Electrical connection to the contact 7 is maintained by spring fingers 88 attached to its base and carrying blocks 89 which slide over a contact rod 90 attached to the cross-bar or outgoing lead. A short stroke of the moving contact 7 may be secured by suitable stops in the member depending from the plate 80. In Figure 17 also, the immediate walls of the arc-

ing chamber are allowed to expand slightly although the gross volume of the arcing chamber, including in this case the volume within the double bellows 83 and 83a, is reduced to cause fluid to be squeezed into the arcing space. An action of this kind is useful in some cases as it allows dissipation of some of the initial high pressure when an arc starts in a confined space while it allows steady movement of the piston for compression purposes.

In Figures 18 and 19, the constructions shown in Figures 3 and 4 and 5 are combined in that there is a main piston 11 sliding within the container wall 2 and returned to the normal position shown by a spring 13, and in addition there are a series of hollow light pistons 11a mounted to slide in the main piston 11. Each of these pistons is provided with its separate returning spring 13a. In this case when an arc is struck, the pressure on the top of the pistons first depresses the light pistons 11a due to their lesser inertia and gives a rapid start off and a quick projection of oil through the passageway in the contacts 16 and later the main piston 11 gets into motion compressing the spring 13 and this goes on until the piston 11 uncovers the exhaust port 25, whereupon all the pistons are returned under the action of their springs into the normal position shown in Figure 18.

In Figure 20, a further form of construction is illustrated in which the differential pressure moves the piston 11 upwards and after exhausting through the ports 25, the piston is restored by its own weight. In this construction, the container 2 has a telescopic lower extension 91 providing a long closed passage for the moving contact 7 without unduly lengthening the main part of the container 2. The piston 11 slides within the container 2 and its tubular extension slides within a downward extension 17 from the cover 15. Thus, when an arc is struck between the contacts 7 and 16, the pressure generated acts on the inner annular part of the upper surface of the piston 11 and is transmitted through the hollow bore of contact 7 and through the ports 92 so as to act upwardly on the whole of the underneath surface of the piston. The piston therefore rises, squeezing the oil within the space inside the piston 11 and inside the extension 17 across the arcing faces of the contacts and down through the centre of the contact 7. When the piston 11 rises above the exhaust port 25, the pressure below the piston is relieved and the latter can return due to its own weight.

In the further form of construction shown in Figure 21, the piston 11 also moves upwards under the differential pressure and is guided in a manner somewhat similar to that in Figure 20, but its inner edge slides up over a further downward extension 93 from the cover 15, which extension carries the hollow fixed contact 16. In this case, the moving contact 7 moves down through a series of baffle plates 44 which are arranged to have an outlet to one side, viz., on the left of Figure 21 in a manner similar to that set forth in our said United States application No. 563,390. When the contacts 7, 16 are separated and an arc struck, the pressure passes through these lateral outlets and the baffle plates 44 into contact with the whole of the underneath surface of the piston 11 and it also passes up through the hollow contact 16 through the ports in the top of the member 17 to the annular surface on the top of the piston 11. The piston is therefore forced up exactly as in Figure 20, but in this case the oil passes through

the ports in the member 17 and down through the hollow contact 16. The construction shown in Figure 21 also allows of a relatively long piston stroke, with only a short stroke of the moving electrode 7 within the arcing enclosure.

Another form of construction is illustrated in Figure 22 embodying another method of obtaining a quick initial movement of the piston and employing a thin metal bellows 39. The construction is otherwise very similar to that shown in Figure 3, as the upper contacts 16 are mounted in the piston 11 which moves downwards against the spring 13. The contacts 16 are connected to the lead-in conductor by pigtails 26. In this case, the bellows 39 are generally of conical shape increasing in diameter towards the bottom. The result is that a relatively rapid initial action is obtained because at the commencement of the stroke of the piston, the upper part of the bellows 39 is collapsed relatively rapidly and quickly forces oil between the contacts. Just as in Figure 3, when the pressure above the piston 11 is released through the exhaust port 25, the spring 13 raises the piston 11 again into the position shown.

In Figure 23, a variation is shown in which the piston can be made to accelerate if required and in which instead of the bellows 39, a series of telescoping members 94 is employed; otherwise the arrangement is much as shown in Figure 22. In this case, therefore as the piston 11 is pushed down, the members 94 telescope in succession into one another. In this case, there is an additional optional feature shown, that is to say, the piston 11 is shown with a depending extension 12a similar to that shown in Figure 2 and for a similar purpose; an auxiliary exhaust outlet 25a is shown so that near the bottom of the stroke of the piston 11, the main exhaust port 25 is covered and exhaust takes place through the constricted outlet 25a providing a dash-pot or buffer effect at the end of the stroke.

In Figures 24 and 25, two further constructions are shown in which the whole casing 2 rises and is guided on the stem 95 from the insulator 1 in a manner somewhat similar to that shown in Figure 9. In fact, these constructions are also adapted for ejecting the dirty used oil at the top of the structure and for that purpose, although it is not shown, parts similar to 40, 41, 43, 97 and 98 in Figure 9 would be fitted. In Figure 24, the greater part of the contents of the arc chamber can be squeezed out while the arrangement shown in Figure 25 is particularly adapted for easy inspection of two main guiding surfaces 95 and 96 on which the container 2 slides. In Figure 24, the piston 11 is stationary, being fixed to the stationary stem 95 and the upper contacts 16 are also rigidly fixed to that piston. Thus, when the movable contact 7 descends to strike an arc between it and the contact 16, the pressure generated by the arc acts on the insulating disc 96 closing the container 2 at the bottom and also has direct access to the underneath surface of the cover 15. The differential pressure, therefore, raises the container 2 against the spring 13, reducing the volume of the space surrounding the contacts 7 and 16 and squeezing oil between the contacts and through the hollow contact 16. This goes on until the container 2 carries the exhaust port 25 above the fixed piston 11 when the pressure above the piston is relieved and the spring 13 is able to return the container 2 into the position shown. If the exhaust is arranged to take place only through the insulator 1 as in Figure 9,

the port 25 is arranged at a lower level so as not to rise above the disc of the piston 11.

In Figure 25, the construction is somewhat different, as the piston 11 extends right down to the bottom of the container 2 and itself is enclosed at the bottom by the insulating disc 96 which therefore remains stationary. In this construction, when the container 2 has reached the top of its stroke, its top passes to the middle of the wide port 43 in the supporting stem 95 and therefore the space above the piston can exhaust around the edges of the top of the casing 2 through the port 43 direct to the outside space.

A further form of construction is shown in Figure 26 which is somewhat similar to that shown in Figures 7 and 8 and here also no flexible connection or pigtail is needed. The whole container 2 moves downwards under the differential pressure against the spring 13 so that the construction forms a compact unit able to lengthen downwards during interruption of the circuit and to recover afterwards. When an arc is struck between the contacts 7 and 16, pressure acts not only on the central part of the cover 15 of the container 2, but also passes through the bore of the contact 7 and through the ports 92 to act on the whole of the surface of the lower wall 4 of the container 2. This sets up the differential pressure causing the container 2 to descend and oil in the outer annular space of the container 2 passes through ports 96 in the piston 11 between the contacts 7 and 16 through the contacts 7 to the space below the piston 11. Exhaust takes place after the arcing tip of the moving contact 7 reaches the space below the piston 11 when the exhausted material passes out through the ports 92.

In Figure 27, a form of construction is shown in which the upper contacts 16 slide on a tubular member 16a, the contact 16 being carried by the piston 11. Thus, when the movable contact 7 descends and strikes an arc and the piston 11 commences to descend, the contacts 16 slide over the member 16a. The latter may be made so long that the contacts 16 never leave it. As shown in the drawings, however, towards the lower part of the stroke of the piston 11, the contacts 16 leave the member 16a so that a second arc will be struck between them in series with the arc between the contacts 7 and 16. The construction may also be slightly modified by arranging for the contact 16 never to rise sufficiently to come into contact with the upper contact 16a, in which case, the moving contact 7 passes through in sliding contact with the contact 16 so as to abut against the upper contact 16a. In that case, the first arc is struck between the contacts 7 and 16a.

In Figures 28 to 30, a series of six units as illustrated in any one of the preceding figures is shown somewhat diagrammatically in order to indicate the preferred method in which the outlet or exhaust ports 25 are disposed. There are shown six complete interrupting points providing for two interruptions per phase in a three-phase system. The switch structures are shown generally at A¹, A² for one phase, at B¹, B² for the next phase and C¹, C² for the third phase. It will be seen that the whole are mounted in pairs in an oil tank 32 of usual construction, the insulators 1 being suspended from the cover 33. The exhaust ports 25 are directed so that products ejected from them will not directly impinge on any other unit of the switch. A₁ of the exhaust ports 25 are directed at angles of 45 degrees to a plane passing through the central vertical axes of the units A¹, B¹, C¹. Viewed as seen in Figure 30, the

exhaust ports 25 of the units A¹, A², B¹, B² are directed forwardly at an angle of 45 degrees and the exhaust ports 25 of the units C¹, C² are directed rearwardly at an angle of 45 degrees.

- 5 The forms of construction already described may be inverted in a simple fashion under certain conditions, for example, when water or a liquid which has slight conducting properties is employed as the fluid, it is necessary for the moving contact to be withdrawn entirely from the liquid after the arc is extinguished as water tends to conduct if it contains even a trace of impurities. A convenient construction for this purpose which may also be used with other liquids and gases is 10 obtained by making use of a well known method of mounting an outer vessel with an open top and containing the liquid upon an insulator. The other parts are the same except that they are inverted and that the lowermost side of the main piston may be slightly domed to provide a gas trap to act as a buffer if required. The moving contact is withdrawn upwardly out of the enclosure entirely and the arc products press the piston in such a direction as to squeeze fluid into the arc gap.

15 It will be appreciated that the invention is not limited to the particular examples outlined above, but that the various details of construction may be altered in many directions. Thus, the forms of construction in which the electrode 16 is carried by the moving piston such as shown for example in Figures 3, 7, 9 10, 16, 18 and 23, can with slight modification be arranged for the speed of closing to be increased with increase of current. Thus, 20 if an auxiliary passageway connecting the arcing chamber and the expanding chamber is provided of such a cross section as to allow liquid to be displaced to enable the contacts 16 and 7 to come together in spite of the effect of throttling the passage through the contact 16. In these 25 circumstances, if any arcing takes place just before the circuit breaker is finally closed, the piston carrying the contact 16 is at once moved forward to meet the approaching movable contact 7. Both in such constructions and in forms in 30 which the contact 16 is not carried by the piston, if any arcing takes place during closing of the switch, oil is immediately forced into the arc gap so as to assist in cooling the contact making surfaces.

35 When a switch, for example, such as shown in Figure 3 is intended to be capable of the accelerated closing action upon closing the circuit, the speed of movement of the movable contact 7 on opening the circuit breaker must be such that with the heaviest currents to be dealt the piston cannot overtake the moving contact.

40 It is possible to provide for automatic limitation of the length of the arc gap to provide a self-adjusting gap and to arrange for the closing of the switch contacts to be assisted by the arcing and for the pressure to accelerate the closing by regulating an auxiliary opening between the contracting and expanding spaces on opposite sides of the piston so that that opening is only opened during, say the first half inch of the piston stroke so that the throttling effect when the contacts approach close together is not effective in preventing contact during this first portion of the piston stroke, but is effective in regulating the arc gap for the rest of the stroke. Thus, for example, in the construction shown in Figure 3, one or more small passageways may be provided leading from the upper surface of the piston 11 down 45 in the thickness of the wall of the container 2

and opening to the inside about a half inch above the top edge of the cylinder which extends up from the bottom plate of the container when the piston is in its uppermost position. In such an arrangement even if the passage through the 50 hollow contact 16 becomes throttled by the close approach of the moving contact 7 on closing the circuit breaker, the piston 11 and contact 16 could move towards the moving contact 7 by an amount of a half inch, while during the opening stroke the throttling of the passage through the contact 16 would serve as a controlling factor as soon as the piston had moved down a half inch so as to cover the port or ports in the side wall.

55 It is possible to minimize an undesirable rise of pressure in the arcing chamber for example during the high current parts of heavy current waves. For this purpose, openings controlled by the pressure in the arcing chamber may be provided between the arcing chamber and the expanding chamber on the other side of the piston. Thus, the normal outlet passageway through the contact 16 or through baffle plates, such as are provided in Figures 10, 12, and 21 may be arranged with valve members or obturators as set 60 forth in our United States Patent application Serial No. 596,855 dated 4th March, 1932. Again one or more auxiliary passageways may be provided arranged to open at a predetermined pressure and to give increased opening into the expanding chamber with further increase of pressure. By suitable choice of the sizes of the opening and of the spring control a small movement of a valve may be arranged to provide a wide variation of opening at high frequency.

65 Another method of avoiding undesirable rise of pressure in the arcing chamber with relatively heavy currents is to provide the arcing chamber with a cushion or yielding piston or pistons opening on one side to the outside of the container 2. Upon occurrence of a high pressure these pistons yield and store energy which is returned to the liquid as the current wave reaches its zero value and oil is squeezed into the arc path. This arrangement does not involve the flow of oil through parts other than across the contact 16. The springs may be given an initial permanent compression so that the pistons only move backwards when the pressure rises above a predetermined value. Care should 70 be taken that the total additional volume afforded by those pistons when they are fully compressed is only a small percentage of the volume of the arcing chamber so that the liquid is kept close to the arc stream ready to be driven back 75 into the arc at about the time of zero current and so that the arc is not left free to strike on to parts that might be left uncovered by the liquid, if the additional piston volume was relatively larger. A small totally closed bellows 80 containing gas or a spring would be suitable for the purpose.

85 Yet again fluid under pressure may be supplied from an external source to the interior of the container 2 to replace the used fluid with clean fluid or to assist the extinguishing action especially at low currents or both in circuit breakers which have to deal with a wide range of current. The fluid will be filled in when required through a non-return valve, the piston or equivalent moving member being conveniently set in motion by or at the time of separation of the electrodes.

90 In addition to the above, the invention is capable of modification as regards detail. It is thus possible to provide a spring co-operating 95

- with the piston so that upon closing the circuit breaker, the spring is slightly compressed and upon opening the circuit breaker is ready to give an initial starting impulse to the piston.
- 5 In forms of construction employing collapsible or telescoping walls, bellows or multiple telescoping parts may be employed. The bellows may have parallel sides or sides diverging or converging towards the arc. In the case of members telescoping within one another increased protection for the main slide member may be obtained by forming it as the inner member and arranging for a flange-like projection of the outer member to slide along it.

- 10 15 In the description above in connection with the drawings, reference has been made to insulating parts, but variations in this direction are possible as the whole or part of the structure may be of insulating material, or again insulating material may be used in other parts to insulate the electrodes from each other while separating and when fully separated.

There have been some references above to the use of seep holes and such holes have been shown 25 in some of the figures of the drawings. However, in circuit breakers adapted to contain fluids of different density such as oil and trapped air and other gas, seep holes are provided to allow the heavier fluid to rise to a predetermined level, 30 generally depending upon whether it is desired to retain a cushion of the less dense fluid or to have the whole space or spaces full of the heavier fluid. Generally speaking for a given volume the smaller the cushion in the expanding 35 chamber on one side of the piston, the greater will be the pressure shock which the walls have to withstand and the more quickly will the piston start to move and vice versa.

Where bellows are not employed, one accurately 40 machined guiding surface is in general sufficient, provided that the space between the other relatively moving surface through which leakage might occur is kept as small as possible to prevent leakage and the egress of fuse metal beads 45 or burnt material from the arc. The insulating clearances between the metal and the arc can be kept small in circuit breakers constructed in accordance with the invention since the movement of fluid in the arcing chamber takes place 50 from the walls towards the arc.

Outlet glands should in general be close fitting to decrease loss of liquid and to increase the efficiency of operation. Whatever the method employed to control the length of arc gap during 55 arcing, the moving contact is preferably moved right out of the container before the completion of its stroke, thus uncovering the opening at the bottom of the arcing chamber and allowing fresh oil to enter the arcing chamber when the piston 60 moves back to its initial position.

To assist adequate clearance in the arcing chamber for a given external container diameter, the movable wall or walls acting to squeeze the contents of the arcing chamber can be mounted 65 below and opening into the arcing chamber and may surround the lower part of the moving electrode, being connected by pressure ducts, connecting rods, lazy-tongs, wires passing over pulleys, differential pulley arrangements and so 70 forth, with a movable part of the chamber at the other end of the container in which expansion takes place. Although when the two surfaces are the opposite faces of a piston they are of unequal areas when the surfaces consist of two members 75 coupled together by a pivoted lever or other op-

erative connection, they may be of equal areas if they are carried on unequal lever arms. If a lazy-tongs arrangement of connecting levers is used, the walls can be made to move away from or towards each other, whichever may be a convenient method of arrangement in a given design. Alternatively, in forms of construction such, for example, as that in Figure 1, all piston movement may be arranged to take place above the solid walled portion of the arcing chamber.

80 In forms of construction, in which a bellows chamber is arranged to expand towards the lead-in insulator during arcing, it is sometimes convenient to use only one upper bellows in which case the current carrying stem which supports the fixed plate or member carrying the fixed electrode may be formed as a wide cage or stirrup, having free space within it for the expansion of the bellows.

85 In another form of construction utilizing the cage or stirrup, the roof of the expanding chamber or bellows mounted on top of a solid walled arcing chamber has a larger area than that of a plunger piston which it carries on its upper surface and which during arcing is moved upwards so as to compress fluid in a small chamber carried beneath the lead-in insulator from which the fluid under pressure is conveniently fed to squeeze the contents of the arcing chamber by ducts formed in one or more of the bars of the 105 cage or stirrup.

90 If a different liquid or other fluid is used in the small chamber and ducts than that employed for extinguishing purposes in the arcing chamber, the ducts may be arranged to open to the back of a 110 piston or pistons which would therefore be moved to compress the contents of the arcing chamber during arcing. In this case the fluid in the ducts would constitute an example of an operative connection other than by rods or the like. If pistons 115 connected with lever arms are employed, the parts may be arranged to slide in a direction at right angles to the axis of electrode separation, or the pistons subjected to differential pressure may themselves slide at right angles, for example, outside the secondary pressure-retaining chamber and drive oil through passages or ducts in the side walls of the container into the arcing chamber.

120 In order to minimize lengthening of the arc 125 when the current wave has a high value, grids or a central member of insulating or conducting material may be placed in the passage of the hollow electrode as close to the fluid inlet mouth as will allow full closure of the electrode. The openings in such grids, or the space between a central member and the sides of the hollow electrode are of sufficient area to allow adequate flow of fluid at high velocity, yet so narrow that a loop of a heavy current arc attempting to press through the 130 opening is short-circuited on itself, and the grids or central member, when of conducting material, are electrically connected to the electrode with which they are associated.

135 Finally, the piston subjected to the differential pressure may be mounted to slide in a seating member held in the container by a catch released near the end of the piston stroke, by the piston itself or by the moving contact or by other means, such as an electromagnetic device so as 140 to allow the seating member with its components completely to leave the container when the circuit breaker is fully opened. A buffer spring bearing against a shoulder on the moving contact 145 may be provided to push the seating member 150

home after the contacts are fully closed and thus to displace fluid out of the container through one or more seep holes at the top.

We claim:—

5. 1. An electric circuit interrupter comprising in combination, a switch container enclosing a confined arcing chamber having a relatively narrow passageway for discharge of fluid therefrom, a pair of arcing electrodes mounted therein, one of 80
10 said electrodes being located in said confined arcing chamber, a movable pumping device housed within said container and operable by the resultant pressure imposed upon it by the products of arcing in said confined chamber and means 85
15 for supplying fluid to said container for extinguishing the arc set up between said electrodes, said pumping device having an effective pumping surface in communication with the space within said arcing chamber and having surfaces so disposed that the resultant pressure due to the 90
20 products of arcing drives said pumping device in such a direction as to cause, during at least part of the time occupied by the movement of said pumping device, reduction in the total volume of 95
25 the space from which fluid is discharged through said passageway after passing through at least a part of the gap between said electrodes and to force the extinguishing fluid into contact with at least one of said electrodes.
30. 2. An electric circuit interrupter comprising in combination, a container enclosing primary and secondary pressure-retaining chambers with a constricted aperture connecting said chambers, a pair of arcing electrodes mounted in said container at least one of which is mounted in said primary pressure-retaining chamber, means for supplying arc-extinguishing fluid to the interior of said container, a movable element furnished with two operatively connected pressure-retaining 100
35 surfaces, one of which is exposed to the space in said secondary pressure-retaining chamber and is moved by the pressure set up by the products of arcing so as to increase the space in said secondary pressure-retaining chamber, while the 105
40 other pressure-retaining surface is exposed to the space in said primary pressure-retaining chamber and is moved by the pressure set up by the products of arcing to such an extent as to cause a reduction of the total space enclosed within the 110
45 walls of said primary pressure-retaining chamber less than the increase in space in said secondary pressure-retaining chamber, the arc-extinguishing fluid being thus squeezed so that it washes over a surface of the electrode immersed in it 115
50 before escaping through the constricted aperture into said secondary pressure-retaining chamber.
3. An electric circuit interrupter comprising in combination, a switch container enclosing a confined arcing chamber having a relatively narrow 120
60 passageway for discharge of fluid therefrom and formed with an internal cylindrical seating, a pair of arcing electrodes mounted therein, one of said electrodes being located in said confined arcing chamber, a piston mounted to slide upon said seating and operable by the resultant pressure set up by the products of arcing in said confined chamber and means for supplying fluid to said container for extinguishing the arc set up between said electrodes, said piston having 125
65 one face in communication with the space within said arcing chamber and having its faces so disposed that the resultant pressure due to the products of arcing drives said piston in such a direction as to cause, during at least part of the 130
70 time occupied by the movement of said piston, 135
75 reduction in the total volume of the space from which fluid is discharged through said passageway after passing through at least a part of the gap between said electrodes and to force the extinguishing fluid into contact with at least one of said electrodes.
4. An electric circuit interrupter, comprising in combination, a switch container enclosing a confined arcing space, a fixed electrode and a movable electrode mounted therein, said movable electrode being located in said confined arcing space and said fixed electrode being formed with a passage, a movable member formed with a pressure-retaining wall housed within said container and operable by the resultant pressure set up by the products of arcing in said confined space and means for supplying fluid to said container for extinguishing the arc set up between said electrodes, said movable member when actuated moving to squeeze the extinguishing fluid in said arcing space and to force it into contact with said moving electrode and into the passage in said fixed electrode.
5. An electric circuit interrupter comprising in combination, a switch container enclosing a confined arcing space, a pair of relatively movable electrodes mounted therein, one of said electrodes being located in said confined arcing space and said other electrode being formed with an axial through-passage, a movable member formed with a pressure-retaining wall housed within said container and acted upon on one surface by the products of arcing in said confined space and having its other surface in communication with said pressure through said axial passage in said electrode and means for supplying fluid to said container for extinguishing the arc set up between said electrodes, said movable member when actuated moving to squeeze the extinguishing fluid in said arcing space and to force it into contact with said other electrode and through said axial passage in said electrode.
6. An electric circuit interrupter comprising in combination, a switch container enclosing a confined arcing space and formed with an internal cylindrical seating, a pair of arcing electrodes mounted in said container, one of said electrodes being located in said confined arcing space and the other electrode being formed with an axial through-passage, a movable member formed with a pressure-retaining wall housed within said container and means for supplying fluid to said container for extinguishing the arc set up between said electrodes, said movable member when actuated moving to cause a blast of extinguishing fluid to flow through said axial passage in said electrode, and the flow through that passage being assisted by the pressure of the products formed by the arc after passing through said passage and having access to the rear surface of said movable member so as to act against the retarding effect of the pressure set up by the products of arcing acting upon the front surface of said movable member.
7. An electric circuit interrupter comprising in combination, a switch container enclosing a confined arcing chamber having a relatively narrow passageway for discharge of fluid therefrom and formed with an internal cylindrical seating, a pair of arcing electrodes mounted therein, one of said electrodes being located in said confined arcing space, a piston mounted to slide upon said cylindrical seating and formed with a rear surface of larger effective area than the front surface thereof, and means for supplying fluid to said

5 container for extinguishing the arc set up between said electrodes, said piston having its face in communication with the space within said arcing chamber so that when moved due to the result-
 10 ant pressure upon its rear face, it causes, during at least part of the time occupied by the movement of said piston, reduction in the total volume of the space from which fluid is discharged through said passageway after passing through at least a part of the gap between said electrodes and to force the extinguishing fluid into contact with at least one of said electrodes.

15 8. An electric circuit interrupter comprising in combination, a switch container enclosing a confined arcing space and formed with an internal cylindrical seating, a movable electrode located in said confined arcing space and a fixed electrode having an axial through-passage and also mounted within said container, means for sup-
 20 plying fluid to said container for extinguishing the arc set up between said electrodes and a pis-
 25 ton mounted to slide upon said cylindrical seating and furnished with a rear surface of greater effective area than the front surface thereof, the products of arcing passing through the passage in said fixed electrode to act upon the rear surface of said piston to exert a resulting pressure tend-
 30 ing to move the piston in order to force the ex-
 35 tinguishing fluid to wash over the surface of at least one of said electrodes before escaping through the passage in said fixed electrode.

40 9. An electric circuit interrupter comprising in combination, a closed container containing arc extinguishing fluid and formed with a cylin-
 45 drical seating and having a relatively narrow pas-
 50 sageway for discharge of fluid therefrom, a pair of relatively movable electrodes mounted in said container so as to separate along the axis of said cylindrical seating and one of which electrodes, at least, is mounted in an enclosed arcing space and a piston mounted to slide on said seating under the action of the pressure set up by the products of arcing in said container in such a direction as to cause, during at least part of the time occupied by the movement of said piston, reduction in the total volume of the space from which fluid is discharged through said passageway after passing through at least a part of the gap between said electrodes in the confined ar-
 55 cing space and to force the extinguishing fluid into contact with at least one of said electrodes.

60 10. An electric circuit interrupter comprising in combination, a switch container enclosing a confined arcing space, a hollow fixed electrode mounted centrally therein, a movable electrode mounted to slide and co-operate with said fixed electrode, a seating member formed with a plurality of axially extending cylindrical seatings, a plurality of light differential pistons having small inertia mounted to slide in said respective seatings and means for supplying fluid to said container for extinguishing the arc set up between said electrodes, the pressure produced by the products of arcing in said container having access to the differential surfaces of each of said pistons so as to actuate said pistons and cause same to reduce the volume of said confined arcing space and to pump fluid into contact with said fixed electrode and through said hollow electrode.

65 70 11. An electric circuit interrupter comprising in combination, a switch container enclosing a confined arcing chamber, a seating member mounted therein and formed with a plurality of axially-directed cylindrical seatings, a hollow fixed contact mounted centrally in said seating, a sliding

75 contact mounted to co-operate with said fixed contact one of the contacts being mounted in the confined arcing chamber, a plurality of dif-
 80 ferential pistons each mounted to slide in one of said cylindrical seatings, a plurality of springs each in operative connection with one of said pis-
 85 tons to return said piston into its normal position, means for supplying fluid to said container for extinguishing the arc set up between said electrodes, the pressure set up by the products of arcing being communicated through said hollow electrode and acting upon said differential pistons to move them against the action of their springs in such a direction as to cause reduction in the volume of said arcing chamber during at least part of the time occupied by the movement of said differential pistons and to pump extin-
 90 guishing fluid into contact with said moving elec-
 95 trode and through said hollow electrode.

100 12. An electric circuit interrupter comprising in combination, a switch container enclosing a confined arcing chamber and formed with an internal cylindrical seating, a movable member formed with a pressure-retaining wall and mounted to slide on said cylindrical seating the spaces on the two sides of said wall being connected by a passageway within said switch container, an electrode carried by said movable member so as to move with it, a sliding electrode mounted to co-operate with said first-named elec-
 105 trode but to separate from same and means for supplying fluid to said container for extinguishing the arc set up between said electrodes, the pressure set up by the products of arcing acting upon said movable member to cause said first-
 110 named electrode to follow up said sliding elec-
 115 trode to maintain a self-adjusting arc gap between said electrodes said fluid for extinguishing the arc being forced by said movable member into contact with said electrodes in the neighbour-
 120 hood of said self-adjusting arc gap.

125 13. An electric circuit interrupter, comprising in combination, a switch container enclosing a confined arcing chamber having a relatively nar-
 130 row passageway for discharge of fluid therefrom, a pair of arcing electrodes mounted therein, one of said electrodes being located in said confined arcing chamber, a movable member formed with a pressure-retaining wall housed within said container and subject to pressure set up by the prod-
 135 ucts of arcing in said confined chamber and ar-
 140 ranged so that upon striking of an arc, the initial movement of said movable member takes place comparatively rapidly and means for supplying fluid to said container for extinguishing the arc set up between said electrodes, said movable member having an effective pumping surface in communication with the space within said arcing chamber and having surfaces so disposed that the resultant pressure due to the products of arc-
 145 ing drives said movable member in such a direc-
 150 tion as to cause, during at least part of the time occupied by the movement of said movable mem-
 155 ber, reduction in the total volume of the space from which fluid is discharged through said pas-
 160 sageway after passing through at least a part of the gap between said electrodes and to force the extinguishing fluid into contact with at least one of said electrodes.

165 14. An electric circuit interrupter comprising in combination, a switch container enclosing a confined arcing chamber having a relatively nar-
 170 row passageway for discharge of fluid therefrom and formed with a plurality of axially-directed cylindrical seatings, a pair of arcing electrodes

- mounted in said container, one of said electrodes being located in said confined arcing chamber, a plurality of differential pistons mounted to slide upon said respective cylindrical seatings and subjected to pressure set up by the products of arcing and means for supplying fluid to said container for extinguishing the arc set up between said electrodes, said pistons being hollow and light so as to be capable of initial rapid movement upon 5 an arc being struck between said electrodes under the resultant pressure due to the products of arcing, in such a direction as to cause, during at least part of the time occupied by the movement of said pistons, reduction in the total volume 10 of the space from which fluid is discharged through said passageway after passing through at least a part of the gap between said electrodes and to force the extinguishing fluid into contact with at least one of said electrodes. 15
- 20 15. An electric circuit interrupter comprising in combination, a switch container enclosing a confined arcing chamber having a relatively narrow passageway for discharge of fluid therefrom, a movable member formed with a pressure-retaining wall and housed within said container, a pair of arcing electrodes mounted in said container, means for supplying fluid to said container for extinguishing the arc set up between said electrodes and a collapsible bellows structure attached to one surface of said movable member and to said container, the arrangement being such that the pressure set up by products of arcing in said confined chamber has access to differential surfaces of said movable member, to drive said movable member in such a direction as to cause, during at least part of the time occupied by the movement of said movable member, reduction in the total volume of the space from which fluid is discharged through said passageway after passing through at least a part of the gap between said electrodes and to force it into contact with at least one of said electrodes. 30
- 35 16. An electric circuit interrupter comprising in combination, a switch container carried by a fixed support and enclosing a confined arcing chamber, a movable member formed with a pressure-retaining wall and exposed to the pressure within said container, a collapsible bellows structure attached to said pressure-retaining wall and to said fixed support, a hollow electrode carried by and movable with said movable member, a sliding electrode mounted to co-operate with said first named electrode and to separate therefrom, means for supplying fluid to said container for extinguishing the arc set up between said electrodes, the pressure set up by the products of arcing between said electrodes passing through said hollow electrode so as to have access to differential surfaces of said movable member in 50 order to actuate the latter in such a direction as to cause, during at least part of the time occupied by the movement of said movable member, reduction in the total volume of the space from which fluid is discharged through said hollow electrode after passing through at least a part of the gap between said electrodes and to force fluid between said electrodes and through said hollow electrode. 60
- 65 17. An electric circuit interrupter comprising in combination, a lead-in insulator, a switch container enclosing a confined arcing chamber having a relatively narrow passageway for discharge of fluid therefrom and mounted to slide relatively to said lead-in insulator, a spring in operative connection with said container to return the 70 latter after operation of the circuit interrupter, a piston having sliding relation with a part of said container and supported from said lead-in insulator, a collapsible bellows structure attached to one surface of said piston and to a part of said container, a hollow electrode providing at least part of a passageway through said piston, a sliding electrode mounted to co-operate with said hollow electrode at least one of said electrodes being mounted within said confined arcing chamber and means for supplying fluid to said confined arcing chamber for extinguishing the arc set up between said electrodes, the pressure set up by the products of arcing acting on differential surfaces to cause relative sliding between said part of said container and said piston in such a direction as to cause, during at least part of the time occupied by said relative sliding movement, reduction in the volume of the space from which fluid is discharged through said passageway after passing through at least a part of the gap between said electrodes and to force the extinguishing fluid into contact with said sliding electrode and through said hollow electrode. 75
- 80 18. An electric circuit interrupter comprising in combination, a lead-in insulator enclosing an internal passageway, a switch container enclosing a confined arcing chamber and mounted to slide relatively to said lead-in insulator, a spring operatively acting on said container to return same after actuation of the circuit interrupter, a piston housed in said container and carried from said lead-in insulator, a hollow electrode providing at least part of a passageway through said piston, a sliding electrode mounted to co-operate with said hollow electrode, a collapsible walled structure attached to said piston and to said container, means for supplying fluid to said confined arcing chamber for extinguishing the arc set up between said electrodes and an automatic valve located in the passageway enclosed by said lead-in insulator, the arrangement being such that the pressure set up by the products of arcing acts on differential surfaces to cause relative sliding between said piston and said container in such a direction as to cause, during at least part of the time occupied by said relative sliding movement, reduction in the volume of the space from which fluid is discharged through said hollow electrode after passing through at least part of the gap between said electrodes and to eject the used extinguishing fluid through the passageway enclosed by said lead-in insulator. 100
- 100 19. An electric circuit interrupter comprising in combination, a switch container enclosing a confined arcing chamber having a relatively narrow passageway for discharge of fluid therefrom, a cylindrical piston mounted to telescope into said switch container, a pair of arcing electrodes mounted in said switch container, one of said electrodes being located in said confined arcing chamber and means for supplying fluid to said confined arcing chamber for extinguishing an arc set up between said electrodes, the pressure set up by the products of arcing in said confined chamber having access to said piston causing said piston to telescope out of said container so as to cause, during at least part of the movement of said pumping device, reduction in the total volume of the space from which fluid is discharged through said passageway after passing through at least a part of the gap between said electrodes. 110
- 115 20. An electric circuit interrupter comprising in combination, a lead-in insulator, a switch container enclosing a confined arcing chamber having a relatively narrow passageway for discharge of fluid therefrom and mounted to slide relatively to said lead-in insulator, a spring in operative connection with said container to return the 120 latter after operation of the circuit interrupter, a piston having sliding relation with a part of said container and supported from said lead-in insulator, a collapsible bellows structure attached to one surface of said piston and to a part of said container, a hollow electrode providing at least part of a passageway through said piston, a sliding electrode mounted to co-operate with said hollow electrode at least one of said electrodes being mounted within said confined arcing chamber and means for supplying fluid to said confined arcing chamber for extinguishing the arc set up between said electrodes, the pressure set up by the products of arcing acting on differential surfaces to cause relative sliding between said part of said container and said piston in such a direction as to cause, during at least part of the time occupied by said relative sliding movement, reduction in the volume of the space from which fluid is discharged through said passageway after passing through at least a part of the gap between said electrodes and to force the extinguishing fluid into contact with said sliding electrode and through said hollow electrode. 125
- 130 21. An electric circuit interrupter comprising in combination, a lead-in insulator, a switch container enclosing a confined arcing chamber having a relatively narrow passageway for discharge of fluid therefrom and mounted to slide relatively to said lead-in insulator, a spring in operative connection with said container to return the 135 latter after operation of the circuit interrupter, a piston having sliding relation with a part of said container and supported from said lead-in insulator, a collapsible bellows structure attached to one surface of said piston and to a part of said container, a hollow electrode providing at least part of a passageway through said piston, a sliding electrode mounted to co-operate with said hollow electrode at least one of said electrodes being mounted within said confined arcing chamber and means for supplying fluid to said confined arcing chamber for extinguishing the arc set up between said electrodes, the pressure set up by the products of arcing in said confined chamber having access to said piston causing said piston to telescope out of said container so as to cause, during at least part of the movement of said pumping device, reduction in the total volume of the space from which fluid is discharged through said passageway after passing through at least a part of the gap between said electrodes. 140
- 145 22. An electric circuit interrupter comprising in combination, a lead-in insulator, a switch container enclosing a confined arcing chamber having a relatively narrow passageway for discharge of fluid therefrom and mounted to slide relatively to said lead-in insulator, a spring in operative connection with said container to return the 150 latter after operation of the circuit interrupter, a piston having sliding relation with a part of said container and supported from said lead-in insulator, a collapsible bellows structure attached to one surface of said piston and to a part of said container, a hollow electrode providing at least part of a passageway through said piston, a sliding electrode mounted to co-operate with said hollow electrode at least one of said electrodes being mounted within said confined arcing chamber and means for supplying fluid to said confined arcing chamber for extinguishing the arc set up between said electrodes, the pressure set up by the products of arcing acting on differential surfaces to cause relative sliding between said part of said container and said piston in such a direction as to cause, during at least part of the time occupied by said relative sliding movement, reduction in the volume of the space from which fluid is discharged through said passageway after passing through at least a part of the gap between said electrodes. 155

electrodes and to force it in contact with at least one of said electrodes.

20. An electric circuit interrupter comprising in combination, a lead-in insulator, a piston carried thereby, a switch container enclosing a confined arcing chamber having a relatively narrow passageway for discharge of fluid therefrom and surrounding said piston and mounted so that during arcing it can slide over said piston in a direction towards said insulator, a spring operatively connected to said container for returning same after reduction of the internal pressure, a pair of arcing electrodes mounted within said container and means for supplying fluid to said confined arcing space for extinguishing the arc set up between said electrodes, the pressure set up by the products of arcing in said confined arcing chamber acting on differential surfaces to cause relative movement of said switch container and said piston in such a way as to cause, during at least part of the time occupied by said relative movement, reduction in the volume of the space from which fluid is discharged through said passageway after passing through at least a part of the gap between said electrodes and to force the extinguishing fluid into contact with at least one of said electrodes.

21. An electric circuit interrupter comprising in combination, a switch container enclosing a confined arcing chamber having a relatively narrow passageway for discharge of fluid therefrom and formed with an internal cylindrical seating and an exhaust outlet in its wall, a piston mounted to slide on said seating and shaped partly to close said exhaust outlet towards the end of its stroke, a pair of arcing electrodes mounted in said container, one of said electrodes being located in said confined arcing chamber and means for supplying fluid to said container for extinguishing the arc set up between said electrodes, the pressure set up by the products of arcing in said confined chamber having access to said piston to drive it in such a direction as to cause, during at least part of the time occupied by the movement of said piston, reduction in the total volume of the space from which fluid is discharged through said passageway after passing through at least a part of the gap between said electrodes and to force the extinguishing fluid into contact with at least one of said electrodes.

22. An electric circuit interrupter comprising in combination, a switch container enclosing a confined arcing chamber having a relatively narrow passageway for discharge of fluid therefrom and formed with an internal cylindrical seating and a plurality of exhaust outlets, a piston mounted to slide on said seating and shaped to close one of said exhaust outlets towards the end of its stroke to produce a cushioning action, a pair of arcing electrodes mounted in said container, one of said electrodes being located in said confined arcing chamber and means for supplying fluid to said container for extinguishing the arc set up between said electrodes, the pressure set up by the products of arcing in said confined chamber having access to said piston to drive it in such a direction as to cause, during at least part of the time occupied by the movement of said piston, reduction in the total volume of the space from which fluid is discharged through said passageway after passing through at least a part of the gap between said electrodes and to force the extinguishing fluid into contact with at least one of said electrodes.

23. An electric circuit interrupter comprising

in combination, a switch container enclosing a confined arcing space, a main arcing electrode mounted therein, a movable electrode mounted to co-operate with said main electrode to strike an arc therefrom, a movable member formed with a pressure-retaining wall housed within said container and subject to pressure set up by the products of arcing in said confined space, means for supplying fluid to said container for extinguishing the arc set up between said electrodes and a stationary additional electrode located in operative relation to said movable electrode to cause the formation of a plurality of arcs in series during the travel of said sliding electrode, said movable member being actuated to squeeze the extinguishing fluid in said arcing space and to force it into contact with at least said stationary additional electrode.

24. An electric circuit interrupter comprising in combination, a switch container enclosing a confined arcing chamber, a differential piston mounted to slide in said container, a fixed electrode mounted in said container, a movable electrode arranged to co-operate with said fixed electrode, a plurality of transverse baffle plates providing at least one narrow passageway between them and located so that said moving electrode travels past the edges of said baffle plates and means for supplying fluid to said container for extinguishing the arc set up between said electrodes, the pressure set up by the products of arcing in said confined space escaping between said baffle plates to drive said piston in such a direction as to cause, during at least part of the time occupied by the movement of said piston, reduction in the total volume of the space from which fluid is discharged through said passageway after passing through at least a part of the gap between said electrodes and to force extinguishing fluid so as to wash over the surface of at least one of said electrodes.

25. An electric circuit interrupter comprising in combination, a substantially cylindrical switch container enclosing a confined arcing chamber, a cylindrical internal structure carried from one end of said container, a plurality of inwardly extending baffle plates carried by said cylindrical structure and venting from said arcing chamber, a fixed electrode mounted in the end of said container, a movable electrode mounted to co-operate with said fixed electrode and to slide past the edges of said baffle plates and a differential piston mounted to slide in the annular space between the inner wall of said switch container and said cylindrical structure, said piston during its travel controlling the outlet from the spaces between said baffle plates.

26. An electric circuit interrupter comprising in combination, a switch container enclosing a confined arcing chamber, a fixed electrode mounted therein, a movable electrode mounted to co-operate with said fixed electrode and to separate therefrom, a plurality of transverse baffle plates of insulating material mounted in said container and extending into the region of travel of said movable electrode, additional electrodes located at the inner ends of said baffle plates to provide for the formation of a plurality of arcs in series, a piston mounted to slide within said container and means for supplying fluid to said container for extinguishing the arc set up between said electrodes, the pressure set up by the products of arcing in said confined chamber escaping through the space between said baffle plates to actuate said piston.

27. An electric circuit interrupter comprising in combination, a switch container enclosing a confined arcing space, a movable member formed with a pressure-retaining wall to slide within said container, an electrode carried by said movable member, a movable electrode mounted within said container to co-operate with said first mentioned electrode, the pressure set up by the products of arcing during closure of the circuit interrupter acting upon said movable member to tend to force the electrode carried by said movable member into contact with said sliding electrode so as to increase the pressure between the electrodes when dealing with currents having heavy root mean square values. 80
28. An electric circuit interrupter comprising in combination, a fixed supporting structure, a movable member mounted to slide upon seating portions of said structure and formed with two unequal surfaces to be acted upon by the products of arcing, a hollow arcing electrode carried in said sliding member and formed with a passage providing communication between the two sides of said movable member, a collapsible bellows structure attached to one surface of said movable member and to said supporting structure, a movable arcing electrode mounted within the space enclosed by said bellows structure to co-operate with said hollow electrode, the arrangement being such that pressure set up by products of arcing within the space enclosed by said bellows structure has access to the unequal surfaces of said movable member to drive the latter in such a direction as to cause, during at least part of the time occupied by the movement of said movable member, reduction in the volume of the space from which fluid is discharged through said hollow arcing electrode after passing through at least part of the gap between said electrodes and to force same between said electrodes and through the passageway in said hollow electrode. 95
29. An electric circuit interrupter comprising in combination a fixed supporting structure, a movable piston mounted to slide on seating portions of said supporting structure and formed with a central passageway, a hollow arcing electrode carried by said piston and having a passageway in registration with the passageway in said piston, a movable electrode co-operating with said hollow electrode, a pair of collapsible bellows structures of unequal diameters attached to opposite faces of said piston and both attached at their remote ends to closure plates forming part of said supporting structure and spring returning means for returning said piston after opening of the circuit interrupter and release of pressure within said bellows structures, the arrangement being such that the pressure set up by products of arcing within one of said bellows structures has access directly to one face of said piston and has access through said passageways to the other face thereby actuating said piston and causing same to slide against the action of said spring returning means. 100
30. An electric circuit interrupter comprising in combination, a container, a relatively movable pumping member forming part of said container and dividing the space therein into primary and secondary pressure-retaining chambers, relatively movable electrodes mounted in said container so that upon opening the interrupter, an arc is drawn at least in part in said primary chamber, a principal path for the extinguishing medium during arcing being provided connect- 105
- ing said primary chamber to said secondary chamber, the arrangement being such that pressure set up by the products of arcing acts on both faces of said movable member while the resultant pressure due to the products of arcing drive said movable member in such a direction as to cause reduction in the volume of said primary chamber during at least part of the time occupied by the movement of said movable member so as to force the extinguishing fluid and the arc products to escape from said primary chamber so as to extinguish the arc. 110
31. An electric circuit interrupter comprising in combination, a container, a movable pumping member mounted to slide therein and dividing the space within said container into primary and secondary pressure-retaining chambers, a stationary electrode mounted in said container, a co-operating movable electrode which is guided at least at the commencement of the opening movement of the interrupter in the wall of said primary chamber so as to make a tight joint therewith, said movable member being provided with a passageway connecting said primary and secondary chambers and being arranged so that pressure set up by the products of arcing acts on both of its faces to drive said member in such a direction as to cause reduction of the volume of said primary chamber during at least part of the time occupied by the movement of said movable pumping member and to force the extinguishing fluid and the arc products to escape from the primary chamber so as to extinguish the arc. 115
32. An electric circuit interrupter comprising in combination, a container enclosing a confined arcing chamber, a pair of arcing electrodes mounted therein, one of said electrodes being located in said confined arcing chamber, a movable pumping device housed within said container and operable by the resultant pressure imposed upon it by the products of arcing in said confined space, means for supplying extinguishing fluid to said container and means whereby energy released by arcing between said electrodes produces an inward gradient of pressure from the walls of said confined arcing chamber towards the root of the arc formed between said electrodes, which pressure throughout arcing has an average magnitude greater at the walls of said confined arcing chamber than at the root of said arc. 120
33. An electric circuit interrupter comprising in combination an enclosure for fluid comprising primary and secondary pressure retaining chambers communicating with each other through a passageway of smaller cross-sectional area than that of the primary chamber, means for rupturing an electrical discharge in said primary chamber in the near neighbourhood of said passageway and a pumping member with two operatively-connected pressure-retaining faces, one of which is exposed to the pressure in the primary chamber and the other to that in the secondary chamber, said pressure-retaining faces being so shaped and operatively connected that upon the occurrence of the said electrical discharge, the pressure generated in the enclosure thereby moves said pumping member so that fluid is moved towards the point of electrical discharge and throughout at least part of the time occupied by the movement of said pumping member, the total volume of the primary chamber is decreased by an amount less than the amount by which the total volume of the secondary chamber is increased. 125
- 75

34. An electric circuit interrupter comprising in combination, a switch container enclosing a confined arcing chamber, a movable member furnished with a pressure-retaining wall arranged to move relatively to a part of said container and having the spaces on its two sides within said container connected by a passageway also within said container, an electrode carried by said movable member so as to move with it, a sliding electrode mounted to co-operate with said first-named electrode but to separate from same and means for supplying fluid to said container for extinguishing the arc set up between said electrodes, the pressure set up by the products of arcing acting upon said movable member to cause said first-named electrode to follow said sliding electrode to maintain a self-adjusted arc gap between said electrodes.

35. An electric circuit interrupter comprising in combination, a substantially fluid-tight container having two chambers communicating with each other through a relatively narrow passageway, said chambers having movable walls operatively interconnected so that upon increase in the internal volume of one of said chambers, decrease in volume of the other chamber occurs, counter-electrodes mounted to separate in the neighborhood of said passageway, one of said electrodes being mounted within said container on a movable part of a wall of one of said chambers, a conducting extension from said last-mentioned electrode extending outside the container, a further outer electrode mounted outside said container and arranged to press said counter-electrodes into contact in the fully closed position of the circuit interrupter and movable with and out of engagement with the said extension, means to separate said counter-electrodes to a predetermined gap and to bring about cessation of electrical contact after a pause by movement of said outer electrode away from the said conducting extension.

36. An electric circuit interrupter comprising in combination, an end plate, a bellows structure having one end closed by said end plate, a partition structure closing the other end of said bellows structure, a second bellows structure attached to the other side of said partition structure, a second end plate closing the remote end of said second bellows structure to form two chambers within said bellows structure connected together by a passageway, electrodes mounted within the space enclosed in said two chambers, means for initiating an electrical discharge be-

tween said electrodes, and means to cause relative movement between said partition structure and said end plates to cause a flow of fluid from one of said chambers into the other of said chambers through said passageway and to direct said flow between said electrodes to rupture said electrical discharge.

37. An electric circuit interrupter comprising in combination, an end plate, a bellows structure having an end closed by said end plate, a partition structure closing the other end of said bellows structure, a second bellows structure attached to the other side of said partition structure, a second end plate closing the remote end of said second bellows structure to form two chambers within said bellows structure connected together by a passageway, electrodes mounted within the space enclosed in said two chambers, means for initiating an electrical discharge between said electrodes, means to cause relative movement between said partition structure and said end plates to cause a flow of fluid from one of said chambers into the other chamber through said passageway and to direct said flow between said electrodes to rupture said discharge, a valve mounted in a wall of one of said chambers and means to open said valve near the end of said relative movement to allow discharge of the arc products from said last-named chamber.

38. An electric circuit interrupter comprising in combination, a pair of collapsible bellows structures, a fixed partition structure between said bellows structure formed with a passageway connecting the interiors of the said bellows structures which, with the said end plates, form a substantially fluid-tight casing containing arc extinguishing fluid, end plates closing the outer ends of said bellows structures, counter-electrodes mounted so that at least part of the path of the discharge between them lies in said fluid-tight casing, one of said electrodes forming at least part of said connecting passageway, means for moving and for slidably guiding said end plates, an operative connection between said end plates, the areas of said end plates exposed to the space within said casing and said operative connection between them being such that the increase of internal volume produced by extension of one bellows structure is greater than the volume by which the interior of the other bellows structure is decreased by said movement.
